FIREPLACE GRATE

Robert H. Taylor, 1106 Summit Lane, Oreland, Pa.

Filed June 15, 1964, Ser. No. 30,405

Term of patent 14 years

(Cl. D81—18)

The sides opposite to the illustration in FIGURES 3 and 4 are the same as the illustration therein. The dominant features of my design reside in the portions shown in full line.

I claim:

The ornamental design for a fireplace grate, substantially as shown and described.
